TRAFFIC SIGNAL

Arthur M. Loungway, Endicott, N. Y.

Application January 12, 1938, Serial No. 184,663

5 Claims. (Cl. 177—327)

The present invention relates to new and useful improvements in signals, particularly for street traffic signals and has for its primary object to provide, in a manner as hereinafter set forth, a device of this character embodying a novel construction, combination and arrangement of parts through the visual medium of which the length of time remaining before the signal changes, or the amount of time that has elapsed since the last 10 change, may be ascertained by a pedestrian or vehicle driver.

Other objects of the invention are to provide a signal of the aforementioned character which will be comparatively simple in construction, strong, durable, highly efficient and reliable in use, compact, light in weight, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein—

25 Figure 1 is a front elevational view of my invention.

Figure 2 is a vertical sectional view taken substantially on the line 2—2 of Figure 1.

Figure 3 is a front elevational view of another 30 form of the invention.

Figure 4 is a side view of the modified form shown partly in vertical transverse section.

Referring now to the drawings in detail it will be seen that the reference numeral 5 designates 35 generally a casing, constructed of metal or other suitable material, having a bottom 6, side walls 7, front wall 8, rear wall 9, and top 10. Electric bulb sockets 11 are mounted in the casing 5 on the rear wall 9 thereof into which are fitted the 40 electric bulbs 12.

The front wall 8 has therein two windows 13 and 14. The window 13 has a green colored lens to indicate "go" while the window 14 has a red colored lens to indicate "stop". The bulbs 12 and reflectors 15 are located behind these windows. A ring of small bulbs 16 surrounds the window 13 and each bulb 16 has a tubular shield 17 around it to make the bulbs more visible when lighted in the daytime. The windows 13 and 14 50 also have tubular shields 18 projecting from the front side of the casing 5 in order that they may be easily seen in the daytime.

In the embodiment shown in Figures 3 and 4 the device is in the form of an attachment 55 which is mounted on a signal lamp. In accord-

ance with this construction a substantially tubular body portion generally referred to by the reference numeral 19 has an annular projection 20 which slidably engages the signal window 21 and is held securely thereto by the screws 22. Around 5 the tubular body portion 19 and constructed integrally therewith is a ring of pockets 23 in which are mounted electric sockets 24 carrying electric bulbs 25. The electric sockets 24 extend through the base 26 of the pockets 23 into an annular 10 groove 27 which is closed by an annular cover 28.

The operation of the device is as follows:

When the green "go" window 13 is lighted one of the small electric bulbs 16 is lighted at the same time, and each of the small electric bulbs 16 is lighted progressively until they are all lighted at which time the green "go" light goes off as well as the small electric bulbs 16. In this way a pedestrian or vehicle driver can observe the amount of time he has to cross an intersection before the "go" light 13 goes off and the "stop" light 14 goes on.

Although I have shown and described herein a preferred embodiment of my invention, it is to be definitely understood that I do not desire 25 to limit the application of the invention thereto, and any change or changes may be made in the materials and in the structure and arrangement of the parts, within the spirit of the invention as claimed.

30 What is claimed is:

1. A traffic signal comprising a casing having upper and lower windows, the upper window having a green lens and the lower window having a red lens, a series of electric bulbs carried by and positioned outwardly of the casing and surrounding said upper windows, individual tubular shields of uniform diameter for said upper and lower windows and individual shields extending from said casing for said electric 40 bulbs.

2. A traffic signal comprising a casing having upper and lower windows, the upper window having a green lens and the lower window having a red lens, a series of electric bulbs carried by and positioned outwardly of the casing and surrounding said upper window, and individual tubular shields for said bulbs and windows extending from said casing in spaced relation to each other.

3. A traffic signal comprising a casing having a window provided with a lens, an annular shield projecting forwardly of the lens, a plurality of lamp accommodating pockets surrounding the shield and lamps carried by the shield and positioned in the pockets.

4. A traffic signal comprising a casing having a window provided with a lens, an annular shield projecting forwardly of the lens, a plurality of lamp accommodating pockets surrounding the shield and lamps carried by the shield and positioned in the pocket, said pocket including forwardly projecting tubular shields of relatively small diameter for the individual lamps.
5. A traffic signal comprising a casing having a window provided with a lens, an annular shield

projecting forwardly of the lens, a plurality of tubular pockets at the peripheral edge of the shield and constituting relatively small lamp shields, the axes of the pocket paralleling the axis of the first named shield, an annular channel rearwardly of the pocket, lamps mounted in the pocket with the base of the lamp projecting into the channel and a rear cover plate for the channel.
